UNITED STATES PATENT OFFICE

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

1,287,617.

Specification of Letters Patent. Patented Dec. 17, 1918.

Application filed December 26, 1914. Serial No. 573,035.

To all whom it may concern:

Be it known that I, REUBEN B. BENJAMIN, a citizen of the United States, residing at Chicago, in the county of Cook and State 5 of Illinois, have invented new and useful Improvements in Electric Switches, of which the following is a full, clear, concise, and exact description, reference being had to the accompanying drawing, forming a 10 part of this specification.

My invention relates to improvements in circuit closers and has for its object to provide a circuit-closing device, particularly for closing the circuit of an electric horn or signaling device. The circuit-closing device is intended primarily for use on automobiles and like vehicles and one of the objects of 15 the invention is to provide a neat, compact switch which may be operable by pressure 20 from most any direction and which is rigidly and economically constructed.

For the purpose of disclosing my invention I have illustrated certain embodiments thereof in the accompanying drawings. In 25 said drawings—

Figure 1 is a perspective view of one embodiment of my invention;

Fig. 2 is a longitudinal sectional view taken on the line 2—2 of Fig. 4;

Fig. 3 is a transverse sectional view taken on the line 3—3 of Fig. 2;

Fig. 4 is a transverse sectional view taken on the line 4—4 of Fig. 2;

Fig. 5 is a longitudinal sectional view taken on lines 5—5 of Fig. 4; and

Fig. 6 is a detail sectional view of a modification.

In the embodiment illustrated in Figs. 1 to 4, I provide a base member 1, which is 40 formed of suitable insulating material and which carries the binding-posts and stationary contact of the switch. This base member is provided with an annular contact member 2 which is seated in a suitable recess 45 in the top of the base member and is provided with an outwardly flared contact lip 3. The inner portion of the contact member, or that part lying flat on the base, is provided with a central opening or cut-out portion 4. The 50 contact member is held in position on the base by a downturned lug 5 which extends through an opening 6 in the base and has its lower end 7 turned over a shoulder 8 formed in the base. A second securing

means for holding this contact member in 55 place is provided which consists of a clip 9 having laterally extending projections 10. This clip extends through an opening in the bottom portion of the contact member, the extensions 10 bearing upon the top of the 60 contact member, and at its lower end is split and passes through a conductor plate 11, the split ends being turned over the conductor plate, as at 12, for clamping the conductor plate in position and also holding the contact member 10 in position. This conductor plate is arranged in a recess on the under side of the base and carries a binding screw 12^a for one of the leading-in wires.

The movable member of the circuit-closer 70 consists of a mushroom-shaped cap 13, which is arranged over the top of the base and is provided with an annular downwardly extending flange 14 extending over the sides of the base but spaced a distance therefrom. 75 This cap carries on its under side and within the recess formed by the annular flange a flat contact 15 which is adapted at its outer periphery to engage with the flange portion 3 of the contact 2. The center of the contact 80 is provided with an integral down-turned sleeve 16 which fits over a hollow post 17 securely mounted in the cap. This post is preferably mounted in the cap by having its upper end provided with an annular flange 85 18 and being molded into the cap. The post projects some distance beyond the cap through the central opening 4 in the contact plate 2 and at its lower end has secured thereon a flat washer 19, which washer engages the lower end of the sleeve 16, the under side of the post being turned over, as at 20, to hold the washer and sleeve in position. This washer 19 extends under a conductor plate 21, which conductor plate is 90 provided with a central aperture for the passage therethrough of the sleeve 16 and the post 18. The conductor plate 21 is held in position in a suitable recess 22 beneath the plane of the contact plate 2 by means of a 100 holding screw 23 countersunk in the base and passing through the base into the contact plate and by means of a second holder and conducting screw 24, which screw engages and holds in position on the under side 105 of the base, in a countersink, a plate 25 and at its opposite end engages in the contact plate 21. The plate 25 also carries a second

binding screw 26 to which the opposite lead-in conductor is adapted to be secured.

By the above means the cap 13 and base are locked together and in order to maintain 5 the cap and base slightly separated I provide a coiled spring 27 which is arranged in the hollow post 17 and bears at its lower end upon a shelf 28 formed in the base. For 10 making a good electrical connection between the conductor plate 25 and the plate 15 the spring 27 at its lower end is adapted to have interposed between it and the base a conductor plate 29, which plate engages beneath the head of the screw 23. It will thus be 15 seen that under all conditions a good electric circuit is maintained from the conductor plate 25 by the way of the screw 24, through the conductor plate 21, the screw 23, the conductor plate 29, the spring 27, the hollow post 17 to the contact plate 15.

By the arrangement above described the cap 13 is maintained in what might be termed a floating position while being at the same time connected to the base. The cap 25 is maintained separated from the base, and with it the contact 15, by means of the spring 27, but whenever pressure is applied to the top of the cap the contact 15 will be moved toward the contact 3 and the circuit 30 thereby closed. Also, if pressure be applied at any point along the side or at any point on the periphery of the cap 13 it will be tilted, the washer 19 forming a fulcrum to prevent the side opposite from that to 35 which the pressure is applied from rising, so that the cap will be tilted on the side on which the pressure is applied, to move the movable contact into engagement with the stationary contact.

40 The button or circuit-closer above described may be secured in any position upon the car or other device on which it is desired to be mounted. For securing it on a flat base I provide a second or sub-base 29 on which 45 the base 1 rests. These two bases are placed in position wherever it is desired and a stirrup having a central opening large enough to slip over the cap and upper part of the base but small enough to prevent the shoulder 50 of the base from passing therethrough is placed in position, this stirrup being provided with laterally extending ears 31 having down-turned flanges 32, which down-turned flanges cover the sub-base 29. Screw 55 openings 33 are provided in the stirrup for the reception of screws to hold the stirrup in position. This stirrup, therefore, forms a clamping member for holding the base in position.

60 It will be noted that the base at 34 is reduced in diameter. This reduction is made for the purpose, where it is desired, of seating the base in its support, an opening large enough for the reduced portion 34 of the 65 base being provided to receive the same.

When the base is mounted in this position the sub-base 29 will be dispensed with and the stirrup, of course, shortened accordingly.

In Fig. 6 I have illustrated a modification of my invention. When it is desired to seat 70 or place the circuit-closing device in the center of the steering post of an automobile it is only necessary to connect one wire of the circuit to the one terminal of the circuit-closer, the other terminal being grounded. 75 In order to seat the device in the steering post the shoulder 30 of the base is left off, so that the base will be straight from top to bottom and thereby readily seat into the steering post. Instead of providing the 80 plate 11 with a binding post, such as 12^a, the plate 11 is provided with an angular upturned extension 35 seated in a recess 36 in the base and provided with a screw opening 37. The base is seated in the top of the 85 steering post and a screw passed through the steering post and engaging in the opening 37, thereby not only locking the circuit-closer in position but also forming a ground 90 connection with this terminal of the circuit-closer.

I claim—

1. The combination with an insulating base, of an annular contact plate mounted on said base and projecting above the surface thereof, a terminal plate mounted on the opposite face of said base, means electrically and mechanically connecting said contact plate and terminal plate together, a locking plate mounted in a recess in the top 95 of said base and within the periphery of said contact plate, a terminal plate on the rear face of said base and means for electrically and mechanically connecting said terminal plate and locking plate together, a cap above 100 said base, a contact plate on said cap co-operating with the contact plate on the base, a center post on said cap loosely extending through an opening in said locking plate, a holding member on said post beneath said locking plate to prevent the separation of the cap and base, and a spring tending to 105 separate said cap and base.

2. The combination with an insulating base, of an annular contact plate mounted thereon, a locking plate mounted on said base having an opening therein, a cap above 115 said base, a center post on said cap loosely extending through an opening in said locking plate and having means on its end for preventing its being separated from said locking plate, a contact plate on the under side of said cap having a truncated portion snugly fitting the post, and a spring tending 120 to separate said cap from said post.

3. The combination with an insulating base, of an annular contact plate mounted thereon, a locking plate mounted on said base, a cap for said base, a center post on 125 said cap loosely extending through an open- 130

- ing in said locking plate, a contact plate on the under side of said cap having a truncated portion snugly fitting said post, a washer on the end of said post beneath said locking plate holding said contact plate in position on the cap and preventing the separation of the cap from the base, and a coiled spring tending to separate said cap from the base.
- 10 4. The combination with an insulating base, of an annular contact plate mounted thereon, a locking plate mounted on said base, a cap for said base, a center post having one end enlarged and embedded in said cap and loosely extending through an opening in said locking plate, a contact plate on the underside of said cap having a truncated portion surrounding said post, the opposite end of said post being enlarged for holding said contact plate in position on the cap and for preventing the separation of said post from said locking plate, and a coiled spring tending to separate said cap from said base.
- 15 5. The combination with an insulating base, of an annular contact plate mounted thereon, an apertured locking plate mounted on said base, a pair of screws passing through said base and holding said plate in position, one of said screws electrically connecting said plate with a terminal plate on the opposite side of the base, a conductor plate secured to the other screw, a cap on
- 35 said base, a contact on the under side of said cap, a hollow post projecting from said cap loosely passing through the aperture of said locking plate, having means for preventing its separation from said plate and in electrical engagement with the cap contact plate, and a coiled spring bearing on said 40 conductor plate and fitting within said post and electrically connecting the cap contact plate with the terminal plate on the base and tending to separate the cap from the base.
6. The combination with an insulating 45 base, of a contact plate mounted on said base and having an annular contact surface extending above the top of said base, a central recess in said base, a locking plate maintained on said base above said recess and 50 having a central opening therein, a cap, a contact plate mounted on the under side of said cap having an annular contact surface, a tubular center post on said cap extending through the opening on said locking plate, 55 a collar on the lower end of the post of greater diameter than the opening in the plate, and a coiled spring in the post tending to separate the cap from the base.
- In witness whereof, I have hereunto sub- 60 scribed my name in the presence of two witnesses.
